UNITED STATES PATENT OFFICE.

EDGAR C. BOGGS, OF NICHOLASVILLE, KENTUCKY.

HAT-MARK

4,004,377

Specification of Letters Patent.

Patented Oct. 3, 1911.

Application filed July 8, 1910. Serial No. 570,611.

To all whom it may concern:

Be it known that I, EDGAR C. BOGGS, a citizen of the United States, residing at Nicholasville, in the county of Jessamine 5 and State of Kentucky, have invented new and useful Improvements in Hat-Marks, of which the following is a specification.

This invention relates to new and useful improvements in hat markers, and has for 10 an object to provide a device adapted to be secured to the sweat-band of a hat and having stamped or printed upon one face the name of the manufacturer or any other advertising matter and having secured to its 15 other face a card upon which may be displayed the name and address of the owner.

Another object of this invention is to produce an article for the purpose disclosed which will not only supply a visual mark 20 of identification but which will be so constructed, that if placed inadvertently upon the head of a stranger, as to inform him of his mistake.

A further object of this invention is to 25 construct a hat-marker comprising but few parts which will be so simple in construction that they can be manufactured at a minimum cost.

With these and other objects in view this 30 invention consists of certain novel constructions, formations and arrangements of parts to be hereinafter more fully described, claimed and illustrated in the accompanying drawing in which,

Figure 1 is a front elevation of my improved hat-marker. Fig. 2 is a rear elevation of the same. Fig. 3 is a section taken on the line 3—3 of Fig. 1. Fig. 4 is a vertical section taken through a portion of a hat 40 having my invention applied to the sweat-band thereof. Fig. 5 is a plan view of the blank from which my hat-marker is made.

Referring to the drawings by characters of reference the numeral 1 designates generally my hat marker, secured to the sweat-band 2 of a hat 3 of any desired shape.

My hat-marker 1 comprises a substantially elliptical plate 4 upon one side of which may be stamped or printed any desired advertising matter. A spring clasp 5 extends from one end of the plate 4 and is adapted to engage and rest upon the upper edge of the

sweat-band 2 of the hat 3 as clearly illustrated in Fig. 4 of the drawing. A card 6 conforming in shape and size to the plate 4 is secured thereto, upon the side opposite the one bearing the advertising matter, by means of retaining fingers 7 several of which are provided with sharpened offset ends 8 for a purpose to be hereinafter described.

The spring clasp 5 is provided with a tongue 9 adapted to be passed through a slot 2' in the upper portion of the sweat-band 2 so as to underlie the latter and hold the device in a position so as not to annoy the wearer.

When it is necessary to place the hat upon a rack or stand containing a number of hats the tongue 9 is disengaged from beneath the sweat-band 2 and the device swung down as indicated by the dotted lines in Fig. 4. It is obvious that the offset ends 8 of the fingers 7 will project inward toward the center of the hat and a stranger inadvertently placing the same upon his head will be apprised of his mistake.

Having thus fully described this invention what is claimed as new is:

1. A device for the purpose described comprising a plate, a card for the reception of printed matter secured to one side of the plate, retaining fingers having sharpened offset ends formed upon the edges of the plate and providing a means for securing the card to the plate, a spring clasp formed integrally upon one end of the plate and adapted to be passed through the sweat-band and constituting a means for hingedly securing the device upon the sweat band of a hat, said clasp including a tongue which is adapted to underlie the sweat band of the hat and hold the device in a position so as not to annoy the wearer.

2. In combination with a hat having a sweat band arranged therein and provided with a slot in the upper portion thereof, of a hat mark hingedly connected to the sweat band and comprising a substantially elliptically-shaped plate, a card for the reception of printed matter secured to one side of the plate, retaining fingers having sharpened offset ends formed upon the edges of the plate and providing means for securing the card to the plate, a tongue formed integrally

on one end of the plate and extending therefrom, said tongue being bent at its point of connection with the plate to form a substantially V-shaped spring clasp, said tongue being inserted through the said slot of the sweat band so as to cause the upper portion of the sweat band between the slot and the upper edge of the band to seat

within the spring clasp to form a hinge for the hat mark for the purpose set forth. 10

In testimony whereof I affix my signature in presence of two witnesses.

EDGAR C. BOGGS.
